14 Claims. (Cl. 270—61)

1

This invention relates to machines for folding the margins of flexible work pieces and more particularly to form folding machines in which a substantial portion of the margin of the work is folded at one time as distinguished from progressive folding.

The principal object of this invention is to produce an improved form folding machine of rugged construction whereby work pieces of heavy type may be satisfactorily folded. In accordance with one feature of the invention, the machine includes a folding lever which is of very rugged construction and which also forms a cover for the driving mechanisms of the machine. This folding lever includes a top portion which extends substantially the entire width and length of the machine, the top portion having formed therewith depending sides which project downwardly inside upwardly extending sides formed with the base.

The folding lever is pivoted upon a shaft carried by a pair of brackets affixed to the base and, in accordance with a further feature of the invention, the folding lever carries at its forward end two separate folding means which are moved about the axis of the said shaft by driving means located inside the machine. The first folding means carried by the front end of the folding lever is arranged to raise the margin of the work piece to a position approximately 90° from the main portion of the work piece which is placed upon a work table held by the base just ahead of the folding means. The second folding means comprises a heavy bar positioned immediately under the first folding means and supported on its under side by an integral portion of the forward end of the folding lever. Separate motive means is connected to the second-mentioned folding means to move the same generally away from and toward the pivot of the folding lever in predetermined time relation to the movement of the folding lever about its pivot. The second-mentioned folding means is arranged to engage the margin of the work piece after it has been turned upwardly by the first-mentioned folding means and by forward movement of the second folding means the upturned margin is placed in overlying position with respect to the adjacent portion of the work piece. Then, upon downward movement of the forward end of the folding lever the under side of the second folding means is firmly pressed against the overlying margin in order to complete the operation.

By virtue of the provision of a folding lever, constructed as described and carrying the two

2

mentioned folding means, a machine capable of folding relatively heavy work pieces without damage to the machine is provided. Also, by the provision of the second folding means vertically movable with the first-mentioned folding means and independently movable forward and backward of the machine to complete the turning over of the margin and to press downwardly thereupon, the adaptability of the machine for its intended purpose is greatly enhanced in that the relatively heavy folding lever need be mounted only for movement about the previously mentioned pivot, in contrast to the machines of the prior art wherein the part generally corresponding to the folding lever of the machine of this invention had imparted thereto up and down movements as well as forward and rearward movements.

By virtue of the described construction of the folding lever, this element also conveniently serves as a cover for a substantial portion of the operating parts of the machine, thereby protecting the parts from damage and foreign matter, as well as lessening the chances of injury to the operator.

Another feature of the invention is that the driving means for moving the folding lever and folding means about the said pivot includes adjustable yielding means for forcing the second-mentioned folding means against the top of the overturned margin.

The illustrated machine also includes clamping means in the form of a presser bar which is carried by a lever pivoted with respect to the base, the lever being manually actuatable to bring the clamping means down upon the upper surface of the work piece on the work table to hold the same in position throughout nearly the entire cycle of operation of the machine. Pivotal carried by the lever is a creasing means in the form of a folding blade, which blade is connected to a driving means including a pivot co-axial with the pivot of the lever carrying the clamping means. By virtue of this construction, upon the initial manual actuation of the machine, the clamping means and creasing means are together moved downwardly to engage the work piece with no relative movement between the clamping means and creasing means taking place, and as the cycle of operation of the machine progresses, the creasing means is moved with respect to the clamping means to permit the second folding means to press the turned margin of the work piece downwardly against the adjacent portion of the work piece.

The above and other features of the invention, including various details of construction and

novel combinations of parts, will now be described by reference to the drawings, and pointed out in the claims.

In the drawings.

Fig. 1 is a front elevation, partly in section, of a machine embodying the invention;

Fig. 2 is a section on the line II—II of Fig. 3;

Fig. 3 is a plan view, partly in section, of the machine;

Fig. 4 is an angular exploded view of a portion of the margin raising bar and associated parts;

Fig. 5 is an angular view, partly in section, of a portion of the margin folding and pressing bar-actuating mechanism;

Fig. 6 is a horizontal section on the line VI—VI of Fig. 2;

Fig. 7 is a section on the line VII—VII of Fig. 6;

Figs. 8 to 13 are detail views of the work-engaging members of the machine showing the various positions thereof relatively to the work piece at different times in the cycle of operation of the machine; and

Fig. 14 is a graph of the positions of the work-engaging members of the machine throughout the cycle of operation thereof.

As shown in Figs. 1, 2 and 3, the machine comprises a flat horizontally disposed base 10, which may be suitably affixed to the top of a work bench. Integral with the base 10 and extending upwardly therefrom are a front wall 12, left side wall 14, right side wall 16, and rear end wall 18. Integral with the front wall 12 and side walls 14 and 16 is a transversely extending bar 20 having on its under side three integral bosses 22. A work table 24 extends transversely of the machine above the bar 20 and is supported by three sleeves 26 each carrying an integral nut 27 the upper ends of which abut against bosses 28 formed integrally with table 24 on the lower side thereof. The bosses 22 are tapped for the reception of the lower ends of the sleeves 26 which are exteriorly threaded, and by rotation of the sleeves 26 the vertical position of the work table 24 may be adjusted. The bosses 28 on table 24 are tapped for the reception of the upper ends of lock screws 30 which pass upwardly through the bosses 22 and sleeves 26 to secure the work table 24 against the upper ends of the nuts 27. As shown, the bar 20 and work table 24 have a slight upward and rearward inclination.

A first folding means in the form of a margin raising bar 34 extends transversely of the machine parallel to the rear surface of the work table 24. Referring also to Fig. 4, the bar 34 is integral with a bracket 36 which is of relatively strong construction and which has a flat rear face around its sides and top, which face is securely held against a forward flat face 38a on a folding lever 38 by screws 40 (Fig. 1). Projections 36a (only one shown) formed on the rear face of each end of the bracket 36 closely fit into corresponding channels 38b formed in each of the flat faces of the lever 38. An opening 42 (Fig. 2) is formed in the bracket 36, through which extends certain of the operating parts of the machine as will be later described.

The folding lever 38 is of relatively strong construction and of hood-like form, and includes side walls 44 and 46 which extend downwardly inside the left and right walls 14 and 16 of the base, respectively, while the rear end 48 of the lever extends downwardly inside the upwardly projecting rear end wall 18 of the base. The folding lever also, therefore, serves as a cover for

most of the operating parts of the machine. An inspection opening 50, which may be provided with a suitable removable cover plate, is provided in the rear top portion of lever 38.

Still referring generally to Figs. 1, 2 and 3, there are disclosed a left bracket 52 and a right bracket 54 affixed to the base 10 by screws 56. These brackets have integral bearings 52a and 54a, respectively, in which is rotatably mounted a shaft 58 extending transversely of the machine and upon which bosses 44a and 46a integral with the left side wall 44 and right side wall 46, respectively, of lever 38 are held. Consequently, the lever 38, bracket 36 and its integral margin raising bar 34 are mounted for pivotal movements about the axis of shaft 58 relatively to the stationary base 10.

The lever 38 (Fig. 4) has a forwardly projecting portion 62 between which and the undersurface of the margin-raising bar 34 is formed a guideway 34a for a second folding means in the form of a folding and pressing bar 64. Formed integrally with and extending rearwardly from each end of the forwardly projecting portion 62 of the lever 38 is a pair of bifurcated lugs 66 (Figs. 2 and 3). Pivoted between each pair of lugs 66 by a pin 68 is the upper forward end of one of a pair of rearwardly and downwardly extending links 70. The lower end of each of the links 70 is pivoted to one of a pair of pins 72, each of which is carried by a pair of arms 74 integral with and extending upwardly from a lever 76 (Fig. 1). The lever 76 is mounted upon an eccentric portion 78 of a shaft 80 journaled in bosses 52b and 54b integral with the previously described brackets 52 and 54 which are affixed to the base 10. The end of shaft 80 projecting to the left of the boss 52b of bracket 52 carries a collar 82 which is held on the shaft by a set screw 84. Collar 82 and the eccentric portion 78 of shaft 80 prevent longitudinal movement of the shaft.

An upstanding lug 86 integral with the lever 76 near the center thereof is provided, and two downwardly and rearwardly extending links 88 have their forward ends pivoted to the rear end of the lug by pin 90. The lower rear ends of links 88 are pivoted to the forward lower end of a cam lever 92 by pin 94. The cam lever 92 carries a pin 95, near the center thereof, upon which is rotatably mounted a cam roll 96 which engages a cam groove in a cam 98 (Fig. 3), affixed upon a cam shaft 100, extending transversely of the machine and journaled in bearings 52c and 54c integral with the brackets 52 and 54. Means for driving the cam shaft 100 will be hereinafter described.

The rear upper end of the cam lever 92 carries a pair of integral fibulations 102 (Fig. 5) between which a block 104 is pivoted by pins 106 which also carry the lower ends of arms 107. The upper ends of these arms are integrally connected by a sleeve 107a freely mounted on a horizontal shaft 108 journaled in bearings 52d and 54d integral with brackets 52 and 54. A pair of collars 107b secured upon shaft 108 by set screws 107c prevent the sleeve, arms and cam lever 92 from moving transversely of the machine. The block 104 is slidably mounted upon a forwardly and upwardly extending rod 109 (Fig. 2) upon the lower end of which is formed a head 110 pivoted upon the shaft 58.

A compression spring 112 encircles rod 109 and is contained in a housing 114, the lower end of which bears against the upper end of block 104

and is slidably mounted on rod 109. The upper end of this rod is threaded for the reception of an adjusting hand nut 116, having a knurled head 117, the lower end of the nut being slidably received within the upper end of housing 114 and passing through plate 118 affixed to folding lever 38. Consequently, housing 114 is free to slide upwardly along rod 109 and the lower end of hand nut 116 by compressing spring 112, the compression of which may be adjusted by manipulation of the hand nut.

For counterbalancing the folding lever and the parts carried thereby, the depending sides 44, 46 of the folding lever 38 are connected to the brackets 52, 54 by springs 122 secured to eyes 124, 126 on the sides of the folding lever and on the brackets respectively. This counterbalancing facilitates lifting the folding lever when making repairs to the machine.

When the cam shaft 100 is rotated, the cam 98 will produce predetermined motions of the cam roll 96 radially of the cam which produce movements of the lower end of cam lever 92 about the pins 106. The motions of the lower end of cam lever 92 are transferred through links 88, lever 76, links 70 and bifurcated lugs 66 to the extension 62 integral with folding lever 38. It will be noted that links 70 and arm 74 of the lever 76 form a toggle which is straightened upon forward movement of the lower end of cam lever 92 resulting in a raising of the lever 38 and the folding and pressing bar 64 and margin raising bar 34 until the toggle moves past dead center, whereupon continued movement draws the lever 38, folding and pressing bar 64, and margin-raising bar 34 downwardly. Rearward movement of the lower end of the cam lever 92 reverses the movements of the parts.

To accommodate pieces of varying thickness, provision is made for turning the eccentric shaft 80 to adjust the position of lever 76 heightwise of the machine, which will in turn vary the positions into which the folding lever 38 is moved as the toggle 70, 74 is straightened and broken. For this purpose, an upwardly extending arm 130 (Fig. 1) is affixed to the right end of the eccentric shaft 80 by a screw 132, which end extends through the upstanding right wall 16 of base 10. Arm 130 carries at its upper end a horizontal bolt 134 which has on its left end a head 136 which projects downwardly into a shoulder 138 of an arcuate plate 140 which is affixed to the side 16 of base 10 by screws 142. The right end of bolt 134 has screwed thereon a hand nut 144 by means of which the head 136 on bolt 134 may be forced into clamping engagement with the adjacent surface of the arcuate plate 140. When the hand nut 144 has been loosened, the arm 130 and shaft 80 may be rotated to vary the position of the lever 76.

The forward edges of the margin-raising bar 34, margin folding and pressing bar 64 and portion 62 of lever 38, and the rear edge of the work table 24 are curved, as shown most clearly in Figs. 8 to 13, about the axis of shaft 58 to prevent any part of the work piece from entering between the mentioned surfaces.

The margin-raising bar 34 has adjustably mounted on its upper face an edge gage 146 in the form of a bar extending transversely of the machine substantially the entire width thereof and having its front edge parallel to and somewhat to the rear of the forward edge of the margin raising bar 34. The work piece is placed upon the work table 24 with its rear mar-

gin overlying the portion of the margin-raising bar ahead of the edge gage 146 and its rear edge abutting the front edge of the edge gage. To facilitate adjustment of the edge gage 146 relatively to the margin-raising bar 34 to vary the width of the margin of the work piece to be folded, the edge gage has secured thereto near each end a rearwardly extending rod 148 which is slidably mounted in the bracket 36 affixed to the front face of the folding lever 38. Coacting with each of the rods 148 is a thumb screw 150 (Figs. 1 and 3) threaded through the adjacent end of the bracket 36. A series of graduations 152 (Fig. 3) is placed at each end of the margin-raising bar 34 to assist the operator in correctly positioning the edge gage 146 upon loosening the thumb screws 150.

Means for reciprocating the margin-folding and pressing bar 64 will now be described. Extending rearwardly from the bar 64 (Figs. 2 and 4), near each end thereof, is a lug 154 which is pivoted to the forward end of a link 156 by means of a pin 158. The rear end of each of the links 156 is pivoted by a pin 160 to the lower end of one of a pair of arms 162 integral with a lever 164 (Fig. 5) pivoted on the shaft 108. The lever 164 includes a downwardly and forwardly extending arm 168 near its right end, the lower end of which carries, by means of a pin 170, a cam roll 172 arranged to ride upon the periphery of a cam 174 (Fig. 3) which is affixed upon the cam shaft 100 by means of set screw 176 passing through the hub 178 formed integrally with cam 174. Attached to the arm 168 at a point above the pin 170 is an eye 180 to which the lower rear end of a tension spring 182 is attached, the upper forward end of the spring being attached to a pin 184 carried by a boss 54h of fixed bracket 54. Spring 182 biases arm 168 to maintain cam roll 172 against the surface of cam 174.

As cam 174 is rotated by the cam shaft 100 and the cam roll 172 is moved inwardly toward the center of the cam by the spring 182, arm 168, lever 164 and the arms 162 carried at opposite ends of the lever move counterclockwise, as seen in Fig. 2, and the links 156 move ahead, resulting in a forward movement of the folding and pressing bar 64. Whenever the cam 174 moves the cam roll 172 outwardly from the axis of the cam the just-described parts move in opposite directions. Cam 174 is positioned upon the cam shaft 100 and has a peripheral pattern such that after the previously described mechanism for raising the margin-raising bar 34 has raised the bar above the surface of work table 24 a predetermined amount, the spring 182 operates the apparatus controlled thereby to move the folding and pressing bar 64 forwardly of the machine to turn the upturned margin of the work piece forwardly. The bar 64 remains in said position until the lever 38 is moved downwardly later in the cycle of operation, whereupon the bar, which is carried thereby, presses downwardly upon the top of the forwardly folded margin of the work piece. Later in the cycle of operation the lever 38 is moved upwardly, and the bar 64 is retracted. The lever 38 is then moved downwardly to the position shown in Fig. 2. Because of the size and strength of the folding lever 38 and its integral portion 62 and because of the size and strength of the bracket 36 and the margin-raising bar 34 formed integrally therewith, the machine is adapted to fold firmly the margins of relatively heavy work pieces. The projections 36a of bar 34 fitted into the channels 39b of lever 38 greatly

strengthen the machine. The use of the folding lever as a cover for the machine is particularly advantageous in that the required shape of the cover, having a hood-like shape in cross-section and depending sides, inherently lends strength to the lever. By arranging the folding and pressing bar 64 for forward and rearward movement independently of the folding lever, and for vertical movement with the forward end of the folding lever, the only movement that must be imparted to the folding lever, in contrast to the prior art machines, is a movement about the axis of the shaft 58.

The following means are provided for regulating the forward travel of the bar 64 according to the width of the margin to be folded. Referring to Figs. 1 to 3 and 5, the arm 168 carries a shouldered bolt 426 retained on the arm by a nut 428. A block 430 is freely mounted on the bolt 426 and this block carries the lower end of a rod 432, the upper end 434 of which is of reduced diameter and is slidably mounted inside the lower end of an adjusting screw 436 which is threaded into a block 438. This block has at each end a stud 440 which is freely mounted in one of a pair of brackets 442 which are affixed to the underside of the folding lever 38 by screws 444. By adjustment of the screw 436 the forward travel of the cam arm 168 may be regulated by the engagement of the upper end of rod 432 with the end of screw 436. This feature of the machine is advantageous since it is desirable that the forward movement of the margin pressing member shall be at least approximately equal to the width of the margin to be folded. If such movement is less than such width, the whole width of the margin will not be pressed against the work piece, and if it is greater than such width, the margin-pressing member may be prevented from pressing the folded-over margin against the work piece in cases where the work piece and margin are beveled or skived in the region of the fold.

A presser bar supporting arm 188 is integrally formed with the presser bar 186 near each end thereof, each of the supporting arms 188 being secured near its upper end by means to be shortly described to the broadened front face 190a of one of a pair of presser bar lever arms 190 each of which is pivoted upon one of a pair of studs 192, one of which is carried by a bearing 52e of bracket 52 and the other of which is carried by a bearing 54e of bracket 54. The presser bar lever arms 190 are formed integrally with a cross-bar 194 extending transversely of the machine between the two arms 190. Each of the presser bar lever arms 190 has a forwardly projecting lug 190b overlying the top end of its associated presser bar supporting arm 188, and each of these lugs is slotted (Fig. 1) for the reception of a vertically extending thumbscrew 198, the lower threaded portion of which extends into the upper tapped end of the associated presser bar supporting arm 188. Also, each of the supporting arms 188 has therein near its upper end a vertically extending slot 188a through which passes a clamping screw 200, the inner end of which is threaded into the front face 190a of the associated presser bar lever arm 190. When the clamping screws 200 are loosened the thumbscrews 198 may be turned to adjust the presser bar-supporting arms 188 and presser bar 186 upwardly or downwardly according to the thickness of the material being folded, and the arms may also be adjusted forwardly and rearwardly.

The creasing means is in the form of a folding blade 202 which is positioned slightly rearwardly of the presser bar 186 and extends parallel thereto, the folding blade being of the same length as the presser bar. The folding blade is slightly curved in cross section, as shown in Fig. 2, and is of relatively thin construction. Two folding blade supporting arms 204 extend upwardly from the folding blade, the left one of these arms being positioned to the right of the left presser bar lever arm 190 and the right one of the arms 204 being positioned to the left of the right arm 190 as shown in Fig. 1. Clamping screws 206, passing through slots 204a, adjustably secure the arms 204 to a folding blade lever 208 (Fig. 3) extending transversely of the machine, the ends of the lever being carried by spindles 210 journaled in bearings 190c near the forward ends of the presser bar lever arms 190. A lug 208b (Figs. 1 and 2) is formed at each end of the lever 208 and projects forwardly over the upper end of the associated arm 204, and each of the lugs is slotted for the reception of a thumbscrew 209 which extends therethrough and into the tapped upper end of the associated arm 204. The vertical and longitudinal position of the folding blade 202 may be adjusted by thumbscrews 209 upon loosening the clamping screws 206.

The folding blade lever 208 has formed integrally therewith an upwardly extending lug 212 (Figs. 1 and 3) in the upper end of which is rotatably mounted a horizontal transversely extending pin 214, the head of which is in the form of a block 214a through which passes a rearwardly and downwardly extending adjusting rod 218 having a knurled head 219. A pair of collars 220 affixed upon rod 218 bear against opposite sides of block 214a to prevent the rod from sliding in the block. The lower rear end portion of rod 218 is screw threaded through the head 224a of a horizontal pin 224 which extends laterally of the machine and is rotatably mounted in the lower forward end of an upwardly and rearwardly extending arm 226 integral with a folding blade cam lever 228 which extends a substantial distance transversely of the machine and has each of its ends pivoted on one of the studs 128. The folding blade cam lever 228, near the right end thereof, has a rearwardly extending arm 232 in the rear end of which is carried a pin 234 upon the left end of which is rotatably mounted a cam roll arranged to bear against the periphery of a cam 238 (Fig. 3) affixed upon cam shaft 100 by set screw 240 which passes through the hub 242 of the cam. The upper end of a tension spring 244 is attached to the right end of pin 234 and the lower end of this spring is held by a pin 246 carried by the bracket 54. Spring 244 maintains cam roll 236 against the periphery of cam 238 at all times, and as cam roll 236 is moved by the rotating cam 238 outwardly from the axis of cam shaft 100, the lever 228 will be moved clockwise about the axis of the studs 128 resulting in a rearward movement of the adjusting rod 218 which produces a counterclockwise movement of the folding blade lever 208 and folding blade 202 about the axis of spindles 210, the folding blade moving relatively to the presser bar 186 and away from the edge gage 143. A movement of cam shaft 236 toward the axis of rotation of the cam shaft under the control of spring 244 moves the just described parts in opposite directions. The peripheral pattern of cam 238 is such that, through the just described system, movements are imparted to the

folding blade 202 in predetermined time relationship to the movements of the other work-piece engaging parts of the machine, as will be later fully described. By rotation of the rod 218 the position of the folding blade 202 may be adjusted longitudinally of the machine in accordance with the width of the margin of the work piece to be folded. Inasmuch as the folding blade 202 is supported by spindles 210 held by the presser bar lever arms 199, any movement of arms 199 about their pivots 192 produces a corresponding movement of the folding blade 202, and when the presser bar 186 and folding blade 202 are in their raised positions, as shown in Fig. 2, the pin 224 and pins 192 are coaxial so that when the presser bar 186 is moved downwardly by arms 190, the folding blade 202 moves therewith without being independently moved about the spindles 210.

Considering now the means for moving the presser bar lever arms 190 about pins 192, the crossbar which interconnects the presser bar lever arms 190 carries an ear 248 to the left of the transverse center thereof to which is pivoted, by a pin 259, an upwardly and rearwardly extending rod 254 slidably mounted in a block 256. A compression spring 258 surrounds the rod 254 and acts between a head 252 formed on the lower end of the rod and the block 253. The upper end portion of the rod is threaded to receive a nut 260 and a lock nut 262 for a purpose to be explained. The forward end of a cam lever 264 is pivoted upon a stud 266 which projects from the left side of block 256, and the cam lever is secured near the middle thereof to a spindle 268 which is rotatably held by a bearing 52f of the fixed bracket 52. A cam roll 270 (Fig. 3) is carried by a pin 272 at the rear lower end of cam lever 264 and is arranged to bear against the periphery of a cam 274 affixed upon cam shaft 100 by screw 276 passing through the hub 278 of the cam.

The forward end of an arm 280 is secured upon the left end of spindle 268 to the left of the fixed bracket 52, and the rear end of this arm carries a pin 282 to which the upper end of a tension spring 284 is attached, the lower end of this spring being attached to a stud 286 carried by the right side of the bracket 52. Spring 284 maintains cam roll 270 against the periphery of cam 274 at all times.

The upper link 288 of a turnbuckle, the lower link of which is numbered 290, has its upper end pivoted upon the left end of pin 282. The lower end of link 288 is left threaded and the upper end of link 290 is right threaded, and connecting the links is an interiorly threaded sleeve 292 upon which is affixed the nut 294. A pair of lock nuts 296 are provided for securing the sleeve 292 in its adjusted position relative to the link members 288 and 290. By means of this arrangement, the length of the turnbuckle may be adjusted, as when assembling the machine.

The lower end of link 290 is pivoted upon a pin 298 carried by a lever 300 secured by pin 302 to a horizontal shaft 306 rotatably held by bearing 52g of bracket 52, as clearly shown in Fig. 6. The rear end of a treadle arm 308 is affixed to shaft 306 by pin 309, and the upper end of a link 310 is screw threaded into the head 312 of a pin 314 which is rotatably held by the forward end of the treadle lever arm 308. Link 310 passes downwardly through the base 10 near the center of the machine and its lower end is connected to a manually actuatable member in the form of a treadle

(not shown), which is arranged, upon depression by the operator, to move the link downwardly.

In operation, when the treadle link 310 is moved downwardly by the operator, the arm 5 303, shaft 306, and lever 309 all rotate clockwise as seen in Fig. 2, and the link members 290, 292 move upwardly, rotating the arm 280, cam lever 264 and spindle 268 clockwise. The lever 264 acts through the spring 258 to rotate the presser bar lever arms 190 clockwise about the studs 192, and the presser bar 186 and folding blade 202 move downwardly to engage the upper surface of the work piece. The operation of cam roll 270 which is moved by cam 274 will be later described.

For driving the cam shaft 100, there is provided a motor 316 (Figs. 2 and 3) carried by a bracket 318 which is affixed to the base 10 by the fastening means 320. The shaft 322 of the motor carries a drive sprocket wheel 324 connected by a chain 326 to a larger sprocket wheel 327 integrally formed with a driving clutch member 328 which is freely mounted to the right of the left side wall 14 of base 10 upon a bearing sleeve 330 affixed in the boss 14a of the side wall. The driving member 328 has affixed therein, 180 degrees apart, two driving pins 329 (Fig. 6) which project beyond the right side of member 328. Mounted in bearing sleeve 330 is the left end of a main drive shaft 332, the right end of which is rotatably held by a bearing 52h formed on the right side of the main bracket 52. A gear 334 is affixed upon the right end of drive shaft 332 by pin 336, and gear 334 meshes with a larger gear 338 (Fig. 3) secured to the cam shaft 100 by set screw 340 passing through the hub 342 of the gear. A driven clutch member 344 (Figs. 6 and 7) is pinned to the main drive shaft 332 by pin 346, and this clutch member is bored parallel to the main driving shaft for the reception of a clutch bolt 348 mounted therein for sliding movement, the clutch bolt being urged to the left by a spring 350 in a bore in the clutch bolt. The right end of spring 350 engages a plate 352 affixed to the right end of the driven clutch member 344 and the driven clutch member has formed therein a slot 354 through which projects a clutch bolt actuating arm 356 integral with the clutch bolt. With the machine at rest, the clutch bolt is held in its retracted position, as shown in the drawings, by the engagement of arm 356 with the wedge shaped member 358, the right side of which member has a laterally inclined surface 358a (Fig. 6) formed at an angle to the surface 358b which is normal to the axis of the main driving shaft 332. This wedge shaped member is attached by screws 360 to the right side of a clutch arm 362 which is pivoted upon a shouldered bolt 364 held by a boss 52i of bracket 52, bolt 364 being held in position by a nut 366 upon the right end thereof. A pin 368 projects from the right side of clutch arm 362 and has attached thereto the lower end of a tension spring 370, the upper end of which is attached to a pin 372 carried by bracket 52. A pin 374 projects from the left side of clutch arm 362 and is arranged to be engaged by the forward end of the lever 300 when the lever is rotated in response to a downward move of the treadle link 310, whereupon the rear end of the clutch arm 362 and the wedge shaped member 358 carried thereby move downwardly displacing the right side of the wedge shaped member from engagement with the clutch bolt arm 356. The

spring 350 moves the clutch bolt 348 to the left into engaging position with one or the other of the drive pins 329 carried by the driving member 328, whereupon the driven clutch member 344, main drive shaft 332, gears 334 and 338 and cam shaft 100 are rotated. As will be later more fully described, upon completion of a cycle of operations of the machine, providing the treadle has been released, the rear end of the clutch arm 362 and wedge shaped member 358 move into their upper positions, resulting in an engagement of the inclined face 358a of the wedge shaped member by the clutch bolt actuating arm 356, and the clutch bolt will be returned to its retracted position as shown in the drawings, whereupon the driven clutch member 344 is disengaged from the driving member 328.

In order to stop the cam shaft 100 from rotating upon a disengagement of the clutch, a collar 376 (Fig. 3) is secured on the right end of the shaft by set screw 378, and formed integrally with the collar is a brake drum 380 against which bears a brake shoe 382 held by an adjustable screw 384 passing through a block 386 formed on the right end of a stud 388 held by the boss 54g of bracket 54. A set screw 390 is provided to hold stud 388 against rotation, and a lock nut 392 is provided on screw 384 for securing the same in adjusted position. Upon loosening the lock nut, the friction of the brake shoe upon the brake drum may be adjusted by means of screw 384. The brake shoe acts on the drum at all times.

In order to prevent the clutch bolt 348 from moving into the path of the driving pins 329 even though the forward end of the clutch arm 362 be moved downwardly, as when adjustments or repairs are being made to the machine, there is provided a rod 394 in an axial bore 395 which extends inwardly from the left end of the main driving shaft 332, the said end of which projects beyond the left side of the left wall 14 of the base 10. The left end of the axial bore 395 in shaft 332 is tapped at 396 for coaction with threads 398 formed on the left end of the rod, and a knurled head 400 is provided on the outer end of the rod. The right end of the rod 394 engages the side of a cross pin 402 which is in a slot 404 passing transversely through and extending lengthwise of the shaft 332. The ends of pin 402 project slightly beyond the periphery of shaft 332 and engage shoulder 406 of a collar 408 slidingly mounted upon the right end of shaft 332 which is somewhat smaller in diameter than the left end thereof. The collar 408 has an integral flange 410 with two slots therein, through each of which projects one of the driving pins 329 mounted in the driving member 328. The left end of a compression spring 412 bears against the right side of flange 410 and the right end of this spring bears against the hub of the driven clutch member 344 in which is formed a recess 414 for receiving the spring and left end of collar 408. By rotating the knurled head 400 the cross pin 402 and collar 408 may be moved to the right along shaft 332 until the right face of the flange 410 is flush with the right ends of the driving pins 329, to move the clutch bolt into its retracted position or to maintain it in such position, as the case may be. The main driving shaft 332 may then be manually rotated by means of a hand wheel 416 which is affixed upon the left end of shaft 332 by screws 418 passing into a flange 420 on the left end of the shaft.

When the machine is at rest, the parts thereof are positioned as shown in Fig. 2. In the use of the machine the operator places a work piece 5 upon the work table 24 with the rear edge of the work piece abutting the forward edge of the edge gage 146 which has been adjusted in accordance with the width of fold to be made. The operator then presses downwardly on the treadle connected to the treadle link 310, and link 310 moves downwardly and by means of the treadle arm 308 the rear arm of treadle lever 300 and the turnbuckle 290, 288 move upwardly, and arm 286, cam lever 264, compression spring 258 and link 254, the presser bar lever arms 190 and the presser bar 186 and folding blade 202 carried thereby are moved clockwise about the axis of studs 192 until the presser bar 186 and folding blade 202 engage the upper surface of the work piece *w*, as shown in Fig. 3. During this initial phase of the downward movement of the treadle link the cam roll 270 will be moved away from the surface of its associated cam 274, and the tension spring 284 will be elongated. Further downward movement of the treadle and treadle link 310 will bring the forward end of the treadle lever 300 into engagement with the pin 374 projecting from the left side of the clutch arm 362, resulting in a downward movement of the wedge-shaped member 358 carried by the clutch arm, whereupon the wedge-shaped member is displaced from engagement with the clutch bolt actuating arm 356 and the compression spring 350 moves the clutch bolt 348 to the left into engagement with one or the other of the driving pins 329 carried by the driving clutch member 328, whereupon the driving shaft 332 and cam shaft 100 are rotated.

As the wedge-shaped member 358, carried by the clutch arm 362, is moved downwardly, the two-part turnbuckle 290, 288 continues to be moved upwardly resulting in a further movement of the cam roll 270 away from the periphery of cam 274 and in a further elongation of the spring 284, and increased pressure of the presser bar 186 upon the work piece is applied.

As soon as the cam shaft 100 commences to rotate the operator will normally release the treadle, but before such releasing the periphery of cam 274 engages the cam roll 270 which through the cam lever 264 and other just-described interconnecting parts increases the pressure of the presser bar 186 against the upper surface of the work piece. However, the use of the compression spring 258 prevents the application of excess pressure by the presser bar upon the work piece, and by means of nuts 260 and 262 such pressure may be regulated. At the same time, through arm 286, the two-part link 288, 290 and treadle lever 300, the cam lever 264 maintains the clutch arm 362 and wedge-shaped member 358 in their downward positions in order that the clutch members continue in engaged position.

Referring also to Figs. 9-14, the margin-raising bar 34 commences to move upwardly when the cam shaft 100 has rotated through about 10° from its starting position, under the control of the cam 98, cam lever 92, links 88, lever 76 and links 78, connected to portion 62 integral with the folding lever 38, the folding lever 38 and parts rigidly connected thereto being pivoted about the axis of shaft 58. The upward movement of the margin-raising bar continues until

the cam shaft has rotated through approximately 50° when the work-engaging parts of the machine will be positioned relatively to the work piece *w* as shown in Fig. 9, and at which time the margin of the work piece will be bent at approximately 90° to the body portion thereof lying upon the work table 24.

When the cam shaft has rotated through about 45° from its starting position, the margin folding and presing bar 64 begins to move forwardly under the control of spring 182 which retains the cam roll 172 against cam 174, the spring acting through the lever 164 and links 156. The bar continues to move forwardly until the cam shaft has rotated through about 80° from its starting position, at which time the work-engaging parts will be positioned as shown in Fig. 10, with the margin of the work piece *w* folded forwardly over the folding blade 202.

The folding blade 202 commences to move forwardly out of engagement with the work from the position shown in Fig. 9 when the cam shaft has been rotated through about 75° , or just before the margin folding and pressing bar 64 stops its forward movement. This movement of the folding blade is controlled by the cam 238 acting through the roller 236, lever 228, and link 216 which moves the folding blade lever 208 and folding blade 202 about the axis of spindles 210, and the forward movement of the folding blade is terminated when the cam shaft has been rotated through about 110° , at which time the work-engaging parts will be positioned as shown in Fig. 11.

Just prior to the termination of the forward movement of the folding blade 202, the toggle members 72, 74 move past their dead center positions and further clockwise movement of the toggle members under the control of cam 98 produces a downward movement of the folding lever 38, and with it the margin-raising bar 34 and the folding and pressing bar 64. The downward movement of these parts continues for a length of time dependent upon the thickness of the margin and body of the work piece adjacent thereto. In the absence of any work piece, the downward movement continues until the cam shaft has rotated through approximately 155° from its starting position. The provision of the spring 112 enables the machine to accommodate itself to firmly folding various thicknesses of material without damaging the machine. At the completion of the downward movement the work-engaging parts are positioned as shown in Fig. 12, the margin of the work piece having been folded over to its final position and pressed downwardly against the underlying portion of the work piece.

Until the cam shaft has rotated through 215° , the work-engaging parts of the machine remain in the positions shown in Fig. 12 during which time pressure is applied to the top surface of the folded-over margin of the work piece to allow it to set in its folded-over position, which margin may or may not have been cemented prior to the introduction of the work piece to the machine, as the occasion warrants.

When the cam shaft has rotated through approximately 215° from its starting position, in the absence of a work piece, the margin-raising bar and margin folding and pressing bar and parts connected thereto are begun to be moved upwardly under the control of cam 98, and at the end of 270° of rotation of the cam shaft these

parts stop their upward movement. It will be appreciated that when a work piece is in the machine the time in the cycle when these parts start their upward movement will depend upon the thicknesses of the margin and body of the work piece adjacent thereto. The folding and pressing bar 64 is begun to be moved rearwardly when the cam shaft has rotated through 255° from its starting position under the control of cam 174 and the interconnecting parts, and the folding and pressing bar reaches its retracted position when the cam shaft has been rotated through approximately 300° . At this point the work-engaging parts will be positioned as shown in Fig. 13.

At this time the margin-raising bar 34 is moved downwardly and reaches its downward position when the cam shaft has rotated through approximately 350° from its starting position. The folding blade is begun to be moved rearwardly under the control of spring 244 and reaches its rearward position when the cam shaft has been rotated through approximately 355° from its starting position. Also when the cam shaft has been rotated through 300° from its starting position, the presser bar 186 begins its upward releasing movement, under the control of spring 284, and it reaches its upward position when the cam shaft has been rotated through approximately 355° . When the cam shaft has been rotated through 355° , the parts will be positioned as shown in Fig. 2.

At the same time that the presser bar 186 commences its upward movement, the arm 280 moves counterclockwise as seen in Fig. 2 under the control of spring 284, producing a downward movement of the turnbuckle 288, 290 and a counterclockwise movement of the treadle lever 300 and arm 308, as well as an upward movement of link 310 and a return of the treadle to its upward position. The end of the treadle lever 300 engaging the pin 374 on the clutch arm 362 moves counterclockwise and the clutch arm 362 is moved clockwise under the control of spring 370. The clutch arm 362 will move the wedge shaped member 358 carried thereby into the path of the clutch bolt actuating arm 356, producing a retraction of the clutch bolt 348 and a disengagement of the same from the driving pins 329 carried by the driving member 328. The brake shoe 332 engaging the surface of the brake drum 380 will stop the rotation of the cam shaft at approximately the starting position. If the operator has not released the treadle, instead of stopping, the cycle of operation of the machine is repeated.

It will be appreciated that the downward movement of the margin raising bar 34 and of the folding and pressing bar 64, when the latter bar is in its forward position, will be arrested by the resistance of the folded-over margin of the work piece when a predetermined amount of pressure has been applied by the folding and pressing bar 64 to the folded-over margin, at which time the upper end of the cam lever 92 moves the pins 106, block 104 and spring housing 114 upwardly and forwardly along the rod 108, against the compression of spring 112, thereby preventing the application of undue pressure to the upper surface of the folded-over margin of the work piece by the folding and pressing bar 64. The amount of pressure to be applied to the surface of the work piece by bar 64 can be regulated by adjusting the compression on spring 112 by means of hand nut 116. In view of this arrangement,

the time when the margin raising bar reaches its downward position with the folding and pressing bar in its forward position varies somewhat according to the thickness of the work piece. If desired, by employing a suitably designed cam for controlling the same, the timing previously set forth may be varied so that the folding and pressing bar 64 moves downwardly more rapidly than described to exert a quick heavy blow on the folded-over margin.

Having thus described the invention, what we claim as new and desire to secure by Letters Patent of the United States is:

1. A form folding machine comprising a base, a work support carried thereby, said work support being adapted to receive a wide work piece, and means for folding the margin of such a work piece on said support, said folding means including a margin turning member, a lever supporting said member, said lever covering substantially the entire base lengthwise and widthwise of the machine and having depending side walls extending toward said base, means mounting said lever for movements relatively to said base, and mechanism mounted on said base under said lever to actuate said lever and margin turning member, said lever cooperating with said base to form an enclosure for said mechanism.

2. A form folding machine comprising a base having upwardly extending side walls, a work support carried by the base, said work support being adapted to receive a wide work piece, and means for folding the margin of such a work piece on said support, said folding means including a margin turning member, a lever supporting said member, said lever covering substantially the entire base lengthwise and widthwise of the machine and having depending side walls extending toward said base adjacent to the walls thereof, means mounting said lever for movements relatively to said base, and mechanism mounted on said base under said lever to actuate said lever and margin turning member, said lever cooperating with said base to form an enclosure for said mechanism.

3. A form folding machine comprising a base, a work support carried thereby, said work support being adapted to receive a wide work piece, a lever covering substantially the entire base lengthwise and widthwise of the machine, means mounting said lever for movements relatively to said base, a first folding means carried by said lever for engaging the margin of such a work piece on said support to turn the margin at an angle to the remainder of the work piece, a second folding means carried by said lever to turn further the margin to complete the folding thereof, and separate mechanisms mounted on said base under said lever to actuate said lever and said first and second folding means together and to move said second folding means independently of the lever and first folding means, said lever cooperating with said base to form an enclosure for said mechanisms.

4. A form folding machine comprising a base, a work support carried thereby, said work support being adapted to receive a wide work piece, a folding lever covering substantially the entire base lengthwise and widthwise of the machine pivoted to said base, mechanism mounted on said base under said lever for moving said lever in opposite directions about its pivot in predetermined time sequence, a first folding means carried by said folding lever for engaging the margin of a work piece on said support to turn the margin

at an angle to the main body portion of the work piece, a second folding means carried by said lever, and mechanism mounted on said base under said lever for operating said second folding means in predetermined time relation to the movements of said lever about its pivot for further turning said margin to complete the folding thereof and position the second folding means for pressing the margin so turned against the adjoining portion of the work piece, said lever cooperating with said base to form an enclosure for said mechanisms.

5. A form folding machine comprising a work support, means for folding the margin of a work piece extending beyond said support comprising a first folder for turning the margin at a right angle to the body of the work piece, means mounting said folder for movement in a path substantially normal to the supporting surface of the work support, a second folder carried by the first folding means for movement therewith and relatively thereto in a path substantially normal to the path of movement of the first folder for completing the fold, and means for moving said folders in predetermined time relation.

6. A form folding machine comprising a work support, a base by which said work support is carried, means for folding the margin of a work piece extending beyond said support comprising a first folder for turning the margin at a right angle to the body of the work piece, means pivoting said folder to said base for movement in a path substantially normal to the supporting surface of the work support, a second folder carried by the first folding means for movement therewith and relatively thereto in a path substantially normal to the path of movement of the first folder for completing the fold, and means for moving said folders in predetermined time relation.

7. A form folding machine comprising a work support, a first folding means for engaging the margin of a work piece projecting beyond the support to turn said margin at an angle to the main portion of said work piece on the support, a second folding means for completing the fold and pressing the margin against the adjoining portion of the work piece on the support, a first means for reversibly moving both of said folding means along a path substantially normal to the surface of the main portion of the work piece, and separate means for reversibly moving said second folding means along a path substantially parallel to the surface of the main portion of the work piece in predetermined time relation to the operation of said first moving means.

8. A folding machine comprising a work support, a first folding means extending transversely of the machine for engaging the underside of the margin of a work piece projecting beyond the support to turn the same upwardly, a second folding means movable with and independently of said first folding means underlying said first folding means for engaging the upturned margin to turn further the same into overlying position with respect to the adjacent portion of the work piece on the support and to press the margin downwardly against the same, and means for operating said first and second folding means in predetermined time relation to one another.

9. A folding machine comprising a base, a work support carried thereby, a first folding means and a member supporting said folding means, said member being reversibly movably mounted with respect to said base to move said first folding

means in a path approximately normal to the work support to turn the margin of a work piece projecting beyond the support at an angle to the main body portion of the work piece upon movement of said member in one direction, a second folding means carried by said member and movable with said first folding means and independently thereof in a direction approximately parallel to the surface of the work support to turn further the margin of the work piece into a position overlying the adjacent portion of the work piece, and for pressing the margin so turned against the adjacent portion of the work piece upon movement of said carrying member in the opposite direction, and mechanism for moving said folding means in predetermined time relation.

10. A folding machine comprising a base, a work support carried thereby, a folding lever pivoted to said base, a first folding means carried by said lever for engaging the margin of a work piece extending beyond said support to turn the same at an angle to the main portion of the work piece upon movement of said lever in one direction about its pivot, a second folding means carried by and independently movable with respect to said lever for engaging the turned margin of the work piece to turn further the same into a position approximately parallel to the adjacent portion of the work piece upon independent movement relatively to the lever, and for pressing the margin so turned against the adjacent portion of the work piece upon movement of said lever in the other direction about its pivot, and mechanism for moving said folding means in predetermined time relation.

11. A folding machine comprising a base, a work support carried thereby, a folding lever pivoted to said base, a first folding means carried by said lever for engaging the margin of a work piece projecting beyond the support to turn the same at an angle to the main portion thereof upon movement of said lever in one direction about its pivot, a second folding means carried by said lever and independently movable with respect thereto in a direction generally toward and away from the pivot between said base and lever for engaging the turned margin of the work piece to turn further the same into a position overlying the adjacent portion of the work piece upon independent movement relative to the lever, and for pressing together the margin and adjacent portion upon movement of said lever in the other direction about its pivot, mechanism for moving said second folding means away from and toward said pivot, and mechanism for moving said folding lever in opposite directions about its pivot in predetermined time relation to the last-mentioned movements of said second folding

means, said last-mentioned mechanism including adjustable means yieldable upon pressing the margin and adjacent portion of the work piece by the second folding means.

5 12. A folding machine for folding wide work pieces comprising a base, a folding lever pivoted to said base, said lever extending substantially the entire distance lengthwise and widthwise of the machine, a first folding means extending substantially the entire distance transversely of the machine and supported by said lever, a second folding means extending substantially the entire distance transversely of the machine underneath said first folding means and supported by said lever, mechanism carried by said base under said lever for reversibly moving said folding lever about its pivot, and additional mechanism carried by said base under said lever for moving said second folding means generally toward and away from said pivot in predetermined time relation to the movements of said lever about its pivot.

10 13. A folding machine comprising a base, a supporting arm pivoted to said base, work clamping means carried by said arm, creasing means pivotally carried by said arm, a folder for turning the margin of the work around said creasing means, manually actuatable means for moving said arm about its pivot to move the clamping means and the creasing means into operative position, and separate means for moving said creasing means about the pivot carried by said arm out of engagement with the work.

15 14. A folding machine comprising a base, a supporting arm pivoted to said base, work clamping means carried by said arm, creasing means pivotally carried by said arm, manually actuatable means for moving said arm about its pivot to move the clamping means into operative position, and separate means pivotally connected to said creasing means about an axis coaxial with the pivot of said arm at the time of actuation of said manually actuatable means for moving said creasing means about the pivot carried by said supporting arm.
